(57) **CLAIM**

The ornamental design for executive chair, as shown.

DESCRIPTION

FIG. 1 is a front isometric view of the executive chair showing my new design also showing chair arms in phantom to depict the typical mounting with the chair;

FIG. 2 is a front elevational view thereof;

FIG. 3 is a right side elevational view thereof with the left side being identical but reversed;

FIG. 4 is a rear elevational view thereof;

FIG. 5 is a top plan view thereof; and,

FIG. 6 is a bottom plan view thereof.

The phantom line shown in FIG. 1 is for illustrative purposes only and forms no part of the claimed design.
